UNITED STATES PATENT OFFICE.

CHARLES F. HANINGTON, OF ROSELLE PARK, NEW JERSEY.

WINDOW-LOCK.

1,077,605.

Specification of Letters Patent.

Patented Nov. 4, 1913.

Application filed March 22, 1911. Serial No. 616,056.

To all whom it may concern:

Be it known that I, CHARLES F. HANINGTON, a citizen of the United States, and a resident of Roselle Park, in the county of Union and State of New Jersey, have invented a certain new and useful Window-Lock, of which the following is a specification.

The object I have in view is the production of a window lock adapted to be used with windows having two sashes, which will effectively lock the windows in closed or open position.

Further objects are to produce a device which will be cheap and highly effective in use, and which cannot be operated except by a person within the room.

These and further objects will appear from the following specification and accompanying drawings, considered together or separately.

In the drawings: Figure 1 is an elevation of a portion of a window frame looking toward the side, with the sashes removed. Fig. 2 is a section on the line 2—2 of Fig. 1, looking in the direction of the arrow. Fig. 3 is a section on line 3—3, of Fig. 1, looking in the direction of the arrow. Fig. 4 is a section on the line 4—4 of Fig. 1, looking in the direction of the arrow. Fig. 5 is a detail view of the operating shaft. Fig. 6 is a detail view of a modification.

In all of the views, like parts are designated by the same reference characters.

In carrying out my invention I provide racks which are carried by the window sashes in a position to one side, out of the way of the counterbalance cords. These racks engage pinions which are carried upon shafts within a box which is mounted within the frame, and behind the parting strip. These pinions have rigidly secured to them ratchets which are engaged by dogs, and the dogs are adapted to be disengaged, when it is desired to open one or both sashes, by cams operated by a handle within the room.

In the drawings, 1 represents the frame, 2 the upper sash, and 3 the lower sash.

4 is the parting strip. Within the frame is located a box, or casing 5. This casing lies behind the parting strip, but is provided with a groove 6, within which the parting strip will lie after having been reduced in width at that point, as shown in

Fig. 3. The casing has a cross member 7, in which the groove 6 is made, and this cross member divides the casing in two parts, producing small chambers 8, 8, one 80 on each side of the parting strip. The sashes are each provided with a rack 9, said racks being located adjacent to the parting strip so that they will not interfere with the sash cord. The racks are provided with 85 teeth, as shown. These teeth are adapted to engage with pinions, 10, 10, each lying within a chamber 8. The pinions are mounted upon a shaft 11, which shaft passes through openings in the walls of the casing, and 70 also in the cross member 7. The pinions are free to turn independently of each other. The pinions engage with the racks, and are rotated as the sashes are raised or lowered. For the purpose of preventing rotation of the pinions and thereby locking both of the windows, each is provided with 75 a ratchet 12, which turns with the pinion. One of these ratchets is a right-handed ratchet, and the other is a left-handed 80 ratchet. In other words,—the teeth on the two ratchets incline in opposite directions. These ratchets are prevented from turning and the windows locked by pawls 13 and 14, one lying in each of the chambers 8. These 85 pawls are supported upon a shaft 15. I prefer to make the shaft 15 so that it will not turn within its bearings, and use it as a support or anchor for spiral springs 16, 16, which surround the said shaft and serve to 90 engage the pawls 13 and 14 with their ratchets. These springs are so arranged that they tend to force the ratchets into engagement with the pawls. For the purpose of moving the ratchets away from the pawls, and thereby unlock the windows, I provide a shaft 17, 95 mounted in bearings in the casing 5, and carrying cams. These cams are in the form of lugs 18 and 19. I prefer to make both lugs upon the same side of the shaft 17, and 100 arrange the lugs so that, by rotating the shaft in one direction, the lug 18 will come in contact with the pawl 13 and disengage it from its accompanying ratchet, and when turned in the other direction, the lug 19 will 105 come in contact with the pawl 13 and disengage it from its ratchet. This shaft I make short and not extending beyond the outer walls of the casing 5, for the purpose of permitting the casing to be easily inserted 110 by a carpenter, into the frame 1. For the purpose of turning the shaft 17, I provide

an extension shaft 20, which is mounted within an opening in the frame, and engages with the end of the shaft 17. For the purpose of making a turning connection between the shafts, I provide the end of the shaft 17 with a notch 21, and the end of the extension shaft 20 with a tongue 22, said tongue lying within the notch and serving as a clutch connection between the extension shaft and the shaft 17. The outer end of the shaft 20 is provided with a handle or button 23. I prefer to make this button oval, as shown, so as to indicate the position of the lugs 18 and 19.

It will be seen that when the shaft 17 is so turned that the two lugs 18 and 19 are not in contact with the two pawls, 13 and 14, that the spiral springs 16 will keep the latter in engagement with the ratchets. The lower sash may thereby be lowered, and the upper sash raised, the pawls idly slipping over the teeth of the ratchets. If, however, the sashes be moved in the opposite direction, these pawls will engage with the teeth of the ratchets and prevent rotation of them in that direction. It is apparent that if the shaft 17 be rotated in one direction and engages the lug 18 with the pawl 13, the latter will be disengaged from contact with its ratchet and, consequently, the lower sash may be raised. When it is raised to the desired extent, the shaft 17 may then be rotated so that the lugs 18 and 19 are in the vertical position out of engagement with the pawls, thus locking the sash in that position. The same action will result if the shaft be turned in the other direction, except the upper sash will be unlocked. The casing 5 is located at the position occupied by the overlap of the two window sashes. Therefore, it is possible to utilize a single horizontal shaft 11, with pinions which will engage upon the racks carried by the two sashes. These racks extend upward and downward so that they pass beyond the point of engagement with the two pinions. I thereby produce a very compact device which will engage with both window sashes and lock the same in position.

In Fig. 6, I show an arrangement in which the two cams or lugs 18 and 19 are on opposite sides of the shaft 17. It is apparent, therefore, that if the shaft be rotated in one direction or the other to about 90 degrees, both pawls will be disengaged from the ratchets, and, therefore, both window sashes can be moved.

I prefer to make the lugs 18 and 19 so that they will not come in contact with the pawls until the shaft 17 is rotated several degrees, so that the pawls will not be disengaged from the ratchets until the shafts are turned to a considerable angle. This will insure the sash being locked, even if a person carelessly fails to turn the shaft 20 so that the button 23 is in an exact upright or horizontal position, which, of course, depends upon the position of the button on the shaft.

In accordance with the provisions of the patent statutes I have described the principle of my invention, together with the apparatus which I now consider to represent the best embodiment thereof; but I desire to have it understood that the apparatus shown is merely illustrative and that the invention can be carried out in other ways.

Having now described my invention, what I claim as new and desire to secure by Letters Patent is:—

1. The combination with two sashes and a rack upon each sash, of a shaft, two independently rotatable pinions on the shaft, said pinions each engaging a rack, two oppositely faced ratchets on the shaft, each ratchet turning with a pinion, a pawl engaging each ratchet in such a manner as to allow movement of a sash in one direction only, a second shaft having lugs thereon, said lugs being engageable with the pawls to disengage the latter from the ratchets and allow movement of the sash in the other direction, a separable key co-operating with the second shaft for rotating said shaft and means carried by the key for indicating the position of the lugs on the shaft with reference to the pawls.

2. A window lock having in combination with a casing and two sashes, a rack on each sash, a pinion engaging each rack, a ratchet on each pinion, an independent pawl normally engaging each ratchet, and a shaft between the pawls, and means whereby rotation of the shaft in one direction will disengage one pawl from its ratchet, and rotation of the shaft in the reverse direction will disengage the other pawl from its ratchet.

This specification signed and witnessed this 14th day of December, 1910.

CHARLES F. HANINGTON.
